Primary Examiner — Alison M Ofstun*(74) Attorney, Agent, or Firm* — Joanne N. Pappas; Kevin C. Johnson(57) **CLAIM**

The ornamental design for a razor, as shown and described.

DESCRIPTION

FIG. 1 is a perspective view of a razor, showing our new design;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof;

FIG. 8 is a rear perspective view thereof; and,

FIG. 9 is a front right perspective thereof.

The broken lines shown in the drawings illustrate portions of the razor forming no part of the claimed design.
